(57) **CLAIM**

The ornamental design for a dispenser with directional flow controlling flange, as shown and described.

DESCRIPTION

FIG. 1 is a perspective view of the dispenser with directional flow controlling flange showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left elevation view thereof; and,

FIG. 7 is a right elevation view thereof.

The appearance within the unshaded region that would be seen in FIGS. 3 and 5 forms no part of the claimed design.
